ELECTRIC GASIFIER

Henri Gamard, Bourges, France

Application May 22, 1930, Serial No. 454,783, and
in France May 30, 1929

4 Claims. (Cl. 48—103)

In the actual apparatus producing hydrocarbon-gases, except those utilizing a wick for ascension of the hydrocarbon by capillarity, the static level of the hydrocarbon is situated above 5 the level of the nozzle for gas-outlet, owing to the fact that the reservoir of hydrocarbon is placed for natural load, or owing to a pressure exerted upon the free surface of the hydrocarbon, the effect being of course the same in both 10 cases. If, in such cases, the burner is extinguished for some fortuitous reason, without the cocks being shut, a dangerous out-flow of the liquid is produced, followed by obvious inconveniences.

15 The present invention relates to a gasifier heated electrically and securing a constant level of the hydrocarbon below the level of the escaping gaseous fluid, even during the utilization.

The gasifying of the hydrocarbon in a tube 20 dipping freely into the reservoir of hydrocarbon is produced by electrical heating of this tube, which heating is adjustable by contacts and a hand-lever, the heating tube together with the heating resistance wound upon this tube by 25 joined turns, being constituted especially for the purpose to develop the greatest heat at the moment of starting, and to distribute thereafter the heat regularly and judiciously during run.

The main feature of the gasifier according to 30 the invention consists in that it contains itself all means for admission, filtration, heating and gasifying of the hydrocarbon, the gasifier constituting in such manner an independent body which is removable and exchangeable at any 35 moment, locked by a multipolar jack serving for admission of the electric current, so as to ensure an automatic breaking of the circuit when removing the gasifier.

Further features will be alluded to in the course 40 of the following description referring to the accompanying drawings representing, in the way of an example, a preferred embodiment of the subject-matter of the invention.

In the drawings:

45 Fig. 1 is a diagrammatic vertical sectional view of the apparatus with the electrical contacts and switch lever detached and shown in plan.

Fig. 2 is a vertical section through a burner provided with a gasifier according to the invention;

Figs. 3 and 4 are two perspective views of the head part of the gasifier.

In Fig. 1, *a* is a reservoir for liquid hydrocarbon, communicating freely at *b* with the atmosphere and adjoining a casing *c* containing a tube

d dipping freely into it and serving for the upward flow and for the gasifying of the liquid hydrocarbon.

In the interior or, preferably, upon the outer surface of the gasifying tube *d* an electrical resistance *e* is provided, furnishing the heat necessary for gasifying, the current being controlled either by an independent resistance or, preferably, with regard to the dissipation of heat, by subdivision of this resistance into three parts 60 *e*₁, *e*₂, *e*₃ included in the circuit either separately or simultaneously by a suitable switch comprising contacts *f*₁, *f*₂, *f*₃, *f*₄ and a hand-lever *g*.

If the hand-lever is upon the dead contact 65 *f*₄, no current flows and the level of the hydrocarbon, *n*—*n*, in the tube is the same as in the reservoir *a*.

If the resistances heat the hydrocarbon and 70 gasify it (by vaporization, by catalysis or in any other way) the gas escapes, at one part, through the nozzle *h* and drives, at the other part, the liquid back in the tube *d*, owing to the relatively small size of the aperture *h*, down to an equilibrium-level *n'*—*n'*, the difference *H* between *n*—*n* 75 and *n'*—*n'* affording a measure of the pressure of the gas at *d'* in the tube *d*. The variation of the current increases or diminishes this pressure and consequently the output at the nozzle *h*.

According to a preferred embodiment the tube 80 *d* open at the bottom and closed at the top consists of red copper and is contained within a protecting sleeve *i* having an annular bottom *i'*, so that an insulating air-layer is maintained between the liquid column contained in the tube *d* to be heated, and the liquid situated around the 85 sleeve *i* and in the reservoir.

Upon the tube *d* covered by a layer *d''* of mica, the resistance wire which is insulated is wound, its adjoining turns or spires covering wholly the 90 surface to be heated, which arrangement has the advantage of securing the emission of a very great heat by a very small mass.

The first fraction *e*₁ of the resistance, the so called starting resistance, (contact *f*₁) covers the 95 tube region contained between the maximum level *n*—*n* and the minimum level *n'*—*n'* of the hydrocarbon in the reservoir.

This starting resistance draws more current 100 than the resistance of utilization and is concentrated in a limited zone in order to carry rapidly this region to a high temperature so as to obtain a nearly instantaneous gasifying.

The utilization resistances can be multiple; two 110

of them are supposed in the embodiment dealt with.

1. For the accelerated run—contact f_2 —use is made of two fractions e_1, e_2 , viz at one part, 5 of the starting resistance and, at the other part, of a fraction e_2 adjoining it at the lower part and wound with the same wire. Consequently the tube is heated in the region $e_1 + e_2$ extending itself at least up to the highest level $n-n$ of the hydrocarbon, in order to avoid the formation of 10 gas bubbles in the lower regions of the tube.

Such a formation of gas bubbles in the lower part of the tube is objectionable because it could drive the liquid and cause its out-flow through 15 the nozzle.

The tube d consisting of red copper is heated in a length sufficient to avoid all risk of condensation, the heating increasing progressively toward the top of the gasifying tube.

20 2. For slow run—contact f_3 —the three fractions e_1, e_2, e_3 are used together. The last fraction e_3 consists of a finer wire than the fractions e_1, e_2 , so that more calories are developed in the region e_3 than in the lower region e_1, e_2 , always 25 with the purpose to avoid driving of the liquid toward the nozzle and to heat more effectively the upper part of this tube, which condition is important for slow run, in order to avoid condensation.

30 The electrical distribution is obtained in the following way:

j are the plugs of a contact plug carried by the head k of porcelain (Fig. 3) surmounting the gasifier, the wire o being connected to this plug, 35 whereas the following wires 1, 2, 3 (Fig. 1) are connected to the contacts f_1, f_2, f_3 situated below the head k (Fig. 3).

The contacts f_1, f_2, f_3 are rubbing against the 40 spring contact l of a hand-lever g of the switch, the contact l being constantly connected to the other pole of the current-source by a contact l' rubbing against a segment q appropriately placed in the circuit.

45 The hand-lever g pivoted at g' is drawn constantly by a spring g'' toward the contact f_2 so as to avoid a useless continued contact with the starting contact f_1 and consequently an exaggerated consummation of current. The spring 50 g'' places hence automatically the lever g upon the contact f_2 as soon as this lever is let out.

The cap k of the gasifier, of insulating material, such as porcelain, protects the contacts and serves as support for the pipe m of the burner m' (Fig. 2); which pipe is suitably centering in the basin k' (Fig. 4) with regard to the spraying hole h .

55 The protecting sleeve i is surrounded at the top and at the bottom by asbestos rings i'' in order to insulate the gasifier from the case c of the reservoir while securing the centering of the gasifier (sufficient play being of course left for the passage of the liquid).

The gasifier constituted in such manner forms 60 an independent whole which is readily accessible and demountable and which remains out of electric contact with the rest of the furnace even if a resistance wire touches fortuitously any metallic part within the gasifier.

70 The head k of the gasifier reposes on a base element p of porcelain or any other insulating material, connected to the reservoir and carrying the contact-segment.

75 Locking of the head k upon the base element p is effected by the socket member r of the contact

80 plug (Fig. 4), serving for conducting the current to the gasifier, so as to break the current automatically when removing the gasifier for inspection or exchange.

For the filtration of the hydrocarbon a filter s is provided in the tube d , this filter supported by a wire s' or the like (for inspection) serving accessorially for the transmission of heat by conductivity into the interior of the liquid mass and for dampening the oscillations of the liquid level 85 in the interior of the tube d .

The invention is of course not limited to the sole embodiment described and represented, since it permits, without deviation from its scope, the most manifold modifications with regard to the 90 whole arrangement, to the details to the shape dimensions and the material employed.

The burner can be straight or of the horizontal type, as represented.

The gasifying tube d can consist of an insulating 95 material (instead of a tube with a double wall d, i).

Finally, use could be made of the conductivity of a metal piece heated by the flame itself of the burner, so as to permit employment of a part 100 of this flame or of its heat for gasifying the liquid column contained in the tube d .

What I claim, is:

1. A hydrocarbon gas producer comprising a reservoir for liquid hydrocarbon, a sleeve closed 105 at its lower end and open at its upper end and provided at its upper end with a supporting plate, a gasifying tube in the sleeve and carried thereby, said tube being open at its lower end and provided with a jet orifice at its upper end, 110 a base element on the reservoir, a head comprising a lower member and an upper member detachable from the lower member, the said supporting plate of the sleeve being secured to the lower member of the head and said lower 115 member being detachably mounted on the base element, a mixing tube into which the jet orifice of the gasifying tube discharges, said mixing tube being detachably mounted on the upper member of the head, heating means for the 120 gasifying tube comprising an electrical resistance on said tube and including contacts mounted on the lower member of the head and a switch lever mounted on the reservoir, each member of the head having an electrode on one side 125 thereof and a contacting cord having a socket member common to both of said electrodes, so that when said socket member is applied to the electrodes it coacts therewith to detachably secure the members of the head together. 130

2. In combination with a reservoir for liquid hydrocarbon, having an opening in the upper wall thereof, a gasifying tube, resistances around the said tube, a support fixed to said wall, a head 135 reposing removably on said support, a mixing tube supported by said head, means to fix said tube and said resistances to said head to permit removal of the whole against the action of gravity, and a contact plug to admit current to said resistances and to also fix said head to said support.

3. In combination with a reservoir for liquid hydrocarbon, having an aperture in the upper horizontal wall thereof, a sleeve closed at the bottom, to plunge vertically through said aperture into said reservoir, a gasifying tube within 140 said sleeve, having an opening in said bottom to establish communication of said tube with said reservoir, filtering means in said tube, electrical resistances in the space between said tube 145 and

and said sleeve, a supporting member fixed to said wall, a head member to repose removably on said supporting member and to support said sleeve, said tube, said resistances and said filtering means and to permit the withdrawal of the whole against action of gravity, means on said head part to support a mixing tube, and a contact plug arranged with one of its contacts in said member and with the other of its contacts in said head part to admit current when inserted and to permit withdrawal of the head part with its adhering parts when withdrawn.

5 4. In combination with a reservoir for liquid hydrocarbon, having an aperture in the upper horizontal wall thereof, a sleeve closed at its lower end and open at its upper end, a gasifying tube in said sleeve and carried thereby, said tube extending down to the bottom of said sleeve and communicating through an opening in said bot-

10 tom with said reservoir, a jet orifice in said tube near its upper closed extremity, electrical resistances between said tube and said sleeve, a supporting member fixed to said wall, a head member to repose removably on said member and to support said sleeve, tube, resistances and filtering means and to permit withdrawal of the whole against action of gravity, means on said head part to support a mixing tube, contacts on said head part, a switch lever in said supporting member to cooperate with said contacts to control the resistances to be included in circuit, and a contact plug insertible with one of its contacts into said supporting member and with the other of its contacts into said head part to admit current when inserted and to permit of the withdrawal of the head part with all its adhering parts when withdrawn.
